Primary Examiner — Darcey E Gottschalk(74) *Attorney, Agent, or Firm* — Nelson Mullins Riley & Scarborough LLP; Thomas J. Engellenner; Reza Mollaaghbabab(57) **CLAIM**

The ornamental design for a cover for a patient limb holder, as shown and described.

DESCRIPTION

FIG. 1 is a top perspective view of a cover for a patient limb holder;

FIG. 2 is a front view;

FIG. 3 is a back view;

FIG. 4 is a left view;

FIG. 5 is a right view;

FIG. 6 is a top view; and,

FIG. 7 is a bottom view.

In the drawings, the broken lines show portions of a cover for a patient limb holder that form no part of the claim.
